[57] CLAIM

The ornamental design for a combined coat and trouser hanger, substantially as shown and described.

DESCRIPTION

FIG. 1 is a front elevational view of a combined coat and trouser hanger showing my new design;

FIG. 2 is a side elevational view taken from the left of FIG. 1;

FIG. 3 is a side elevational view taken from the right of FIG. 1;

FIG. 4 is a top plan view thereof;

FIG. 5 is a bottom plan view thereof;

FIG. 6 is a vertical sectional view thereof taken along line 6—6 of FIG. 1;

FIG. 7 is a rear elevational view thereof.

FIG. 5

FIG. 6

FIG. 7
